UNITED STATES PATENT OFFICE.

JOSEPH ROCH BRIEN, OF MONTREAL, QUEBEC, CANADA, ASSIGNOR OF ONE-HALF TO
LYDIA FLAMONDON, NÉE HARDY, OF MONTREAL, CANADA.

MACHINE FOR DRYING PEAT.

Application filed September 29, 1922. Serial No. 591,394.

To all whom it may concern:

Be it known that I, JOSEPH ROCH BRIEN, a subject of the King of Great Britain, residing at Montreal, Province of Quebec, 5 Canada, have invented certain new and useful Improvements in Machines for Drying Peat; and I do hereby declare that the following is a full, clear, and exact description of the invention, such as will enable others skilled in the art to which it appertains to 10 make and use the same.

The present invention pertains to improvements in machines for drying peat or similar substances, and has for its object 15 the provision of a machine of this character which receives the peat in its crude condition and compresses it automatically.

The machine receives the peat in a crude state and first presses it in order to expel 20 the moisture. The peat is then dried on an apron or conveyor which is movable in a stream of warm gas escaping from a special generator, no further operation being necessary than charging the machine with crude 25 peat and removing the dried peat ready for the market.

Further objects and advantages of the invention will appear as the description continues, while others will be particularly 30 pointed out. The invention is fully disclosed in the following description and in the accompanying drawings in which:

Figure 1 is a longitudinal sectional view of one end of the machine;

Figure 2 is a longitudinal section of the other end of the machine;

Figure 3 is a section on the line 3—3 of Figure 1; and,

Figure 4 is a perspective view showing 40 the conveyor construction.

The machine comprises three principal parts, namely, a compressor 1, a drier 2, and a vapor or steam generator 3. The compressor shown in Figure 1 of the drawings 45 consists of a hollow cylinder 4 at the upper part of which is formed a mouth or entrance opening 5. The cylinder is mounted in a suitable support 6 which not only supports the cylinder 4, but also serves as a bearing 50 7 in which is mounted the shaft 8 of a double spiral 9 extending into the cylinder. On the shaft 8 is fixed a pulley 10 which is turned by a belt from any desired or suitable source of power, whereby the spiral member 9 is turned.

At the forward position of the cylinder 4 is supported a tapered neck member 11 in which is formed a plurality of longitudinal compartments 12 which are square in cross section (Figure 3) by means of the perpendicularly intersecting longitudinal partitions 13. A chute 14 is suspended at the smaller end of the neck and is adapted to be cut off therefrom by means of the plate valve 15. This valve is closed in case the charge of 65 peat in the cylinder 4 is exceedingly wet. Under these conditions, the peat being wrapped within the cylinder gives off some of its moisture which escapes through the nipples 16.

The forward end of the chute 14 extends into the housing 17 of the conveyor system 2 in which is mounted the endless carrier 18 on the rotatable sprocket wheel 19. The conveyor consists of a pair of spaced sprocket chains 20 (only one of which is shown in Figure 4) which support a plurality of separate latticed members 21. Each of the latter is provided with a perpendicular flange 22, also latticed, to avoid sliding of the material being carried. Beneath the endless conveyor is mounted a plate 23 which serves to support the peat when it is on the lower way. This plate is curved upwardly as at 24 at the forward end in order to retain the 85 material while rounding the forward sprocket wheel, and is turned downwardly as at 25 at the rear end for a purpose later to be pointed out.

Beneath the forward end of the conveyor 90 is disposed the heating system 3 which consists of a boiler comprising inclined vapor tubes 26 surrounded by concentric water tubes 27. The latter are placed in communication with one another at their ends 95 by means of the headers 28, the lower one of which is fed by the water inlet pipe 29. An inclined steam pipe 30 extends from the upper header to a steam chest 31 mounted in the top of the casing 17. A steam supply 100 pipe 32 extends from the steam chest to the lower part of the furnace where it enters an air passage 33 whereby a mixture of air and steam is drawn into the fire box. The fuel inlet consists of a double wall pipe 34 105 within the central member 35 of which is disposed a steam pipe 36 closed at its inner end as at 37. The space between the two outer pipes also receives steam and this space is likewise closed at its inner end. The peat, 110.

which is used as fuel, is forced through the space between the two inner pipes from a device such as that shown in Figure 1 or by any other suitable means. The moisture which is eliminated from the peat by means of the steam is allowed to escape through the passage 38 which is shielded by a plate shown at 39 for the purpose of preventing peat being forced outside the pipes 34 and 35. Likewise the condensate formed in the outer annular space may escape through the nipple 40, while the plate 41 prevents the direct escape of steam. The peat enters on the grate 42 where it comes under the influence of the mixture of air and dry steam entering from the pipes 32 and 33. Some of this mixture is utilized in the combustion process, as is well known in the art, but the major portion serves to dry the material carried through the conveyor system 2. The mixture after having become saturated with moisture from the peat escapes through the flue 43 at the rear end of the conveyor housing. A baffle plate 44 is adjustable along the inclined water tube and is actuated by means of the link 45. A by-pass 46 establishes communication between the steam chest 31 and the lower header 28, so that a water gauge 47 may be inserted between it and the steam supply pipe 32.

A sprayer 50 is disposed adjacent the turned end 25 and communicates with a source of oil, illustrated by the tank or barrel 51, by means of the piping 52. As the peat reaches the end of its course on the conveyor, having been freed of its moisture content, it is treated with oil from the sprayer 50 as it passes over the lip 25. From the latter it passes into a chamber 53 from which

it is withdrawn through a door 54, shown in dotted lines, and is now ready for use.

While a specific embodiment of the invention has been illustrated and described, it is to be understood that various alterations in the details of construction may be made without departing from the spirit of the invention as indicated by the appended claims.

Having thus fully described the invention, what I claim as new and desire to protect by Letters Patent is:—

1. In a machine for drying peat, a conveyor, a water heater disposed beneath said conveyor, a steam chest communicating with said heater, an air passage at the lower portion of said heater, and a steam supply pipe extending from the steam chest to the air pipe.

2. A machine for drying peat comprising a conveyor, a water heater beneath said conveyor, a steam chest in communication with said heater, a fire grate in said heater, an air pipe leading to the lower portion of said fire grate, and a feed supply pipe extending from the steam chest to the air pipe.

3. In a machine for drying peat, a conveyor, means for heating the peat on said conveyor, and means at the end of the conveyor for spraying oil.

4. A machine for drying peat comprising a conveyor, a supporting plate beneath said conveyor, said plate having a downwardly extending lip formed at its rear end, a heating device disposed beneath said conveyor, and a sprayer disposed adjacent said lip.

In witness whereof I have hereunto set my hand.

JOSEPH ROCH BRIEN.
